UNITED STATES PATENT OFFICE.

WILLIAM B. DURGIN, OF CONCORD, NEW HAMPSHIRE.

DESIGN FOR A SPOON.

SPECIFICATION forming part of Design No. 20,685, dated April 21, 1891.

Application filed March 30, 1891. Serial No. 387,028. Term of patent 7 years.

To all whom it may concern:

Be it known that I, WILLIAM B. DURGIN, of Concord, in the county of Merrimac and State of New Hampshire, have invented a new and original Design for Spoons, of which the following is a full, clear, and exact specification.

Reference is to be had to the accompanying drawing, forming a part of this specification, in which the figure represents a face view of a spoon embodying my new design.

The most prominent features of the design are the bowl ornamentation and the ornamentation of the outer end of the handle.

The letter *a* indicates the bowl ornamentation, the same consisting of a marine view, including the representation of a caravel having its sails set.

The letter *b* indicates a figure representing Columbus as if standing on the deck of a

vessel, *b'* indicating the deck, *b²* a rope guard, *b³* a rope ladder, and *b⁴* an anchor.

The edge of the spoon-handle is beaded at the outer end, as indicated by the letter *c*, said bead representing a rope, which at the inner end of the handle is represented as winding around the latter.

Adjacent to the representation of the anchor is the figure *d*, representing an hour-glass, the scroll *e*, and the figure *f*, representing a branch in foliage, a ribbon figure *g* appearing as if entwining the branch.

I claim—

The design for the ornamentation of spoons, as herein shown and described.

WILLIAM B. DURGIN.
